TARGET

William F. Winning and Carl Keyser,
Braddock, Pa.

Application July 19, 1934, Serial No. 736,114

4 Claims. (Cl. 124—15.5)

Our invention relates to targets and more particularly to a target of the type disclosed in Patent No. 1,949,554, wherein a visual means is provided for indicating when the target is struck by a projectile and it consists in the constructions, arrangements and combinations herein described and claimed:

It is an object of the invention to provide a target embodying a plurality of "bull's-eyes" each of which are associated with a visual indicator which will be displayed upon striking of the "bull's-eyes" by a projectile, and further provides a novel and simplified means for retaining the bull's-eyes in operative position, yet quickly releasable upon striking thereof to cause projection of a visual means beyond the target proper.

It is a still further object of the invention to provide a target especially suited for indoor amusement which will be simple of construction, and embodying visual indicators of comical caricatures whereby interest and pleasure may be afforded children as well as adults.

Additional objects, advantages and features of invention will be apparent from the following description considered in conjunction with the accompanying drawing, wherein

Figure 1 is a front elevation of our target, one of the comical caricatures or indicators being shown in projected position.

Figure 2 is a rear elevation thereof.

Figure 3 is an enlarged detail of one of the indicators.

Figure 4 is a cross section on the line 4—4 of Figure 2.

Figure 5 is a detail perspective view of one of the detent means for the indicator.

Upon the rear face of the target 10 there are mounted a plurality of visual indicators 13, including a caricature portion 14 and a bull's-eye portion 15, these indicators being so fixed to the target that the caricature portion 14 will be projected beyond the target 10 upon striking of the bull's-eye portion 15, and in order that the indicators 13 may be thus released, the target 10 is provided with a plurality of apertures 16, which in the operative position of the indicators aligns the bull's-eye portion 15 with respective apertures 16.

Inasmuch as the visual indicators are identical in construction, a detailed description of one will be ample for a full and complete understanding of the construction and operation thereof, and attention is now invited particularly to Figure 3 of the drawing.

A pair of bearings 17—18 are secured to the rear face of the target 10, and within these bearings there is rockably journaled a shaft 19, the intermediate portion of which has formed therein a crank 20. The bearing 17 it will be noted is spaced a slightly greater distance away from the crank portion 20 than the bearing 18, permitting the installation of a helical spring 21 upon the shaft between the crank 20 and the bearing 18. The spring 21 includes an arm 22 and an arm 23, the arm 22 being in engagement with the crank portion 20 and the arm 23 having bearing contact with the rear face of the target. The arm 22 is associated with the crank so that the spring normally tends to project the indicator beyond the edge of the target.

One extremity of the shaft 19 terminates in a right angular lug 24, which in conjunction with the rear face of the target, functions to limit the movements of the indicators either in their projected or retracted positions.

The caricature portion 14 and the bull's-eye portion 15 are connected by a reduced body 25, and at a suitable point thereon, a bearing 26 is secured, receiving the crank 20.

The bull's-eye portion 15 has a finger 27, extended rearwardly therefrom adapted to align with a detent means 28 located at a point upon the opposite side of the aperture 16. The detent means 28 in the present instance includes a base 29, from which there are arranged upstanding parallel ears 30. The finger 27 is adapted to be positioned between the ears 30, there being sufficient friction between the ears and finger to hold the indicator in retracted position against the action of the spring 21.

As may be seen from Figures 1 and 3, the apertures 16 are arranged in a semi-circular formation and consequently the indicators 13 are positioned in a radial formation upon the rear face of the target, although it should be understood that the location or arrangement of apertures and indicators may be varied to suit conditions of manufacture or otherwise.

In the set or operative positions of the indicators, the bull's-eye portion 15 will be positioned directly over an aperture 16 so that it may be readily struck by a projectile which action will cause a back swing of the bull's-eye 15, releasing the finger 27 from the detent 28. Upon release of the finger the spring 21 which is under tension will project the caricature portion 14 beyond the outer edge of the target. In order to reset the indicators the indicator is swung radially inward toward its respective aperture

16 until its finger 27 is engaged by the detent 28. Obviously, such movement of the indicator places the spring 21 under tension to project the caricature portion 14.

5 17 From the foregoing, it will be seen that we have provided a target of simplified form well adapted for indoor use, and which will afford amusement to children as well as grown-ups.

18 It will be understood that the caricature portions 10 may embody representations of persons, objects or numerals. In the latter event making it possible for a group of players to enter into a contest to determine who can shoot the highest score, which would be done by a totalling of the 15 various numerals displayed by the shots of each respective contestant.

20 While we have shown and described a preferred construction of the invention, we do not limit ourselves to the exact structure shown and described, and consider as our own, all such modifications as fairly fall within the scope of the appended claims.

25 We claim:—

1. A target having an aperture, and an indicator, said indicator having a bull's-eye portion and a caricature portion, the bull's-eye portion normally being disposed in alignment with the aperture, a shaft pivotally mounted to the target, said shaft having a crank portion swingably connected with the indicator means, detent means for releasably holding the indicator in operative position, and spring means associated with the shaft for rocking the crank portion to project the caricature portion of the indicator beyond 30 the outer edge of the target, said shaft having means for limiting movement of the indicator in either direction.

2. A target comprising a plurality of apertures, indicator means associated with each aperture, said indicators each including a bull's-eye and caricature portion, a plurality of shafts os- 35

cillatably mounted upon the target and associated with each indicator means, each shaft having a crank connected to each indicator, the bull's-eye portions normally being aligned with respective apertures, a finger on the bull's-eye portions, detent means releasably holding the finger of the bull's-eye portions, spring means associated with the crank of the shaft for imparting rocking movement thereto for projecting the caricature portion beyond the edge of the target upon striking of respective bull's-eyes, and means associated with the shaft for limiting movement of the indicator.

3. A target comprising a plurality of apertures, 15 indicator means associated with each aperture, said indicators each including a bull's-eye and a caricature portion, a plurality of shafts rockably mounted upon the target, said shafts having a crank portion upon which respective indicator means are pivoted, said bull's-eye portion normally overlying its respective aperture, a radially extended finger on the bull's-eye portion of each indicator, detent means receiving said finger, and spring means associated with each shaft to rock the same for projecting the caricature portion beyond the edge of the target upon striking of respective bull's-eyes.

4. A target comprising a plurality of apertures, indicator means associated with each aperture, said indicators each including a bull's-eye and a caricature portion, a plurality of shafts rockably mounted upon the target, each shaft having a crank portion upon which respective indicator means are pivoted, said bull's-eye portion normally overlying its respective aperture, a radially extended finger on the bull's-eye portion of each indicator, detent means receiving said finger, and said shaft having means for limiting movement of the indicator in either direction.

30 WILLIAM F. WINNING.

35 CARL KEYSER.
